RATCHET LOCK FOR RECORD BINDERS

Ernest M. Allen, Jr., Nashville, Tenn., assignor to
The Marshall & Bruce Company, Nashville,
Tenn., a corporation of Tennessee

Application April 29, 1932. Serial No. 603,163

6 Claims. (Cl. 129—13)

This invention relates to a ratchet lock for record binders.

In record binders of that type involving expandable and contractible side members, some means are usually provided for quickly locking the same in any adjusted position.

This invention concerns itself primarily with novel means for quickly and automatically locking the two parts of the binder in any adjusted position and which means may be quickly released for unlocking the binder.

The invention comprises the novel structure and combination of parts hereinafter described and more particularly pointed out and defined in the appended claims.

In the accompanying drawing which illustrates a preferred form of this invention and in which similar reference numerals refer to similar features in the different views:

29. Figure 1 is a fragmentary interior plan view of a loose-leaf binder involving this invention.

Figure 2 is a fragmentary interior plan view with a portion cut away at the end to illustrate the locking mechanism.

25. Figure 3 is a sectional view taken upon the line III—III of Figure 1 looking in the direction of the arrows.

Figure 4 is an enlarged sectional view taken upon the line IV—IV of Figure 1 looking in the 30 direction of the arrows.

Figure 5 is an enlarged fragmentary sectional view taken upon the line V—V of Figure 1 looking in the direction of the arrows.

Figure 6 is an enlarged sectional view taken 35 upon the line VI—VI of Figure 1 looking in the direction of the arrows.

In referring to the drawing which illustrates a preferred embodiment of this invention, there is illustrated only certain parts of the binder 40 which are deemed necessary to explain this invention. The rear portion of the binder comprises a pair of angular members which slide over each other during the adjustment of the binder. The angular member upon one side of 45 the binder is designated by the reference numeral 1 and consists of a vertical portion and a horizontal portion 2. The other side of the binder comprises a vertical portion 3 which terminates in a horizontal portion 4 which is superposed upon the portion or flange 2 for relative sliding movement with respect thereto.

The vertical portions 1 and 3 carry post holding bars 5 which are removably attached by means of screws 5a as shown in Figure 1. The 55 bars 5 carry telescopic posts consisting of the

tubular portions 6 and the inner cylindrical portions 7 as shown in Figure 3.

The flange 2 is bent upwardly and inwardly at each end to provide an overlapping portion 2a as shown in Figures 4 to 6. The plate 4 60 which is carried by the vertical flange 3 is cut away at each end as shown in Figure 2 and the main portion of the cut away edge is provided with ratchet teeth 8 as shown in Figure 2. A pawl 9 is located beneath the inturned flange 2a 65 in the space defined by the cut away portion of plate 4. With reference to Figure 2, it will be noted that this pawl 9 is relatively long and is pivoted at one end to the plate 2 as indicated at 10. The other end of the pawl 9 is provided with 70 ratchet teeth 11 which are adapted for engaging the teeth 8. A spring 12 secured to the pawl 9 normally bears against the plate 2 for normally maintaining the pawl in engagement with the ratchet teeth 8.

A slide 13 is positioned at each end of the binder upon the inturned flange 2a. Each slide has an upwardly extending finger portion 14 whereby the same may be readily grasped by the operator. The slide 13 is also provided with a 80 guide slot 15 for receiving a guide pivot 16 extending upwardly from the inturned flange 2a. Each slide 13 is also provided with a cam slot 17 which is provided with an inclined edge 18 and each pawl 9 is provided with a pin 19 at 85 each head thereof for projecting through the cam slot 17 of its respective slide 13.

In the position of the parts as shown in Figure 1, the pawl 9 is in locking engagement with the ratchet 8, and it will be noted that in this 90 position the pin 19 upon each pawl is located in the bottom of the cam slot 17. To unlock the pawls 9 from engagement with the ratchet teeth 8, the slides 13 are moved toward the left. During such movement of the slides 13, the inclined 95 edges 18 or cam portions of said slots will move the pins 19 outwardly and disengage the pawls 9 from the plate 4 in order to allow the two sides of the binder to be expanded or contracted. After the binder has been properly 100 adjusted, the slides 13 are slid backwardly to the position shown in Figure 1 for allowing springs 12 to engage the pawls 9 with the plate 4.

Between the head of one pawl 9 and the casing there is shown a permanent locking member 105 20 which may be in the form of a pin, bolt or the like. The casing is provided with an aperture 21 adjacent each pawl for the insertion of such pin. It will be understood that during the normal use of the binder such pins 20 are not 110

present. They are intended to be inserted after the binder has been filled and is to be stored away at which time it is desirable to permanently lock the same. When the binder is to be stored away, suitable pins 20 may be inserted in the apertures 21 and behind the heads of the pawls 9 and broken off flush with the casing so they cannot be easily removed for permanently locking the pawls 9 and thereby permanently locking the binder.

It will readily be appreciated that the two slides 13 may be easily and quickly operated to release the pawls 9 from their locking engagement with the plate 4 and for holding the same in disengaged position while the binder is expanded or contracted. By thuswise positively maintaining the pawls in inoperative position it is a very simple and easy matter to adjust the binder since it is impossible for the pawls to positively move into locking engagement with the plate 4, when the slides are in their unlock-
ing position.

I am aware that many changes may be made and numerous details of construction may be varied through a wide range without departing from the principles of this invention, and I, therefore, do not purpose limiting the patent granted hereon otherwise than necessitated by the prior art.

I claim as my invention:

1. In a binder having a pair of relatively slid-
able back plates, one of said plates having ratch-
et teeth upon one edge, a pawl pivoted at one
end to the other plate and having ratchet teeth
at its other end for engagement with said
ratchet teeth on said aforementioned plate, a
slide supported over said pawl, said slide hav-
ing a cam slot and said pawl having a pin ex-
tending into said cam slot whereby the actua-
tion of said slide will operate said pawl.

2. In a loose leaf binder having relatively slid-

able back plates, one of said plates being shorter than the other and having ratchet teeth upon one edge, a pawl pivoted upon the other plate for engaging said ratchet teeth, a slide, and means for mounting said slide above said pawl, said slide having a cam slot and said pawl having a pin extending into said slot for the purpose set forth.

3. In a binder having shiftable back plates, one of said plates having inturned ends over-
lapping the other plate, a pawl upon said first
mentioned plate for locking engagement with
the other plate, a slide mounted upon one in-
turned end and means for connecting said pawl
and slide for the purpose set forth.

4. In a loose-leaf binder having a pair of rela-
tively slidable back plates in superposed relation,
one of said plates having ratchet teeth upon its opposed ends, pawls mounted upon the
other plate for engaging said ratchet teeth, pawl
actuating slides and means for supporting one
slide over each pawl, said pawls and slides having
cooperating means for operating the pawls
during the shifting of said slides.

5. In a loose leaf binder having shiftable back
plates, one of said plates having ratchet teeth
upon one end, a pawl pivoted to the other plate
for engaging said ratchet teeth, said last men-
tioned plate having an upturned end and means
between said pawl and upturned end for lock-
ing said pawl against operation.

6. In a binder comprising a pair of shiftable
back plates, one plate having ratchet teeth upon
one edge, the other plate extending beyond said
ratchet teeth, a pawl pivoted to said last men-
tioned plate for engaging said ratchet teeth, and
a slide mounted upon the binder and having a
connection with said pawl for retracting the
same from engagement with said ratchet teeth.
